UNITED STATES PATENT OFFICE.

JOSEPH WALL, OF BOOTLE, COUNTY OF LANCASTER, ENGLAND.

JURY-RUDDER.

SPECIFICATION forming part of Letters Patent No. 367,871, dated August 9, 1887.

Application filed March 17, 1886 Serial No. 195,661. (No model.)

To all whom it may concern:

Be it known that I, JOSEPH WALL, of Bootle, in the county of Lancaster, England, have invented certain new and useful Improvements in 5 Jury-Rudders; and I do hereby declare that the following is a full, clear, and exact description of the invention, which will enable others skilled in the art to which it appertains to make and use the same, reference being had to the accompanying drawings, and to letters of reference marked thereon, which form a part of this specification.

Figure 1 is a side elevation of a part of a ship's hull with my invention attached thereto. Fig. 2 is a plan of the clamp for holding the rudder, which is attached to the vessel under its stern-quarter, and which is bolted to the dead-wood or stern-post. Fig. 3 is a plan of the clamps for securing the blade of the rudder to the stem thereof. Fig. 4 is a plan of the bearing for the rudder-stem, that is attached to the stern of the vessel near the top of the rudder-stem. Fig. 5 is a vertical section of the socket, into which the lower end of the rudder-stem is stepped, and of the thimble and lower end of the rudder-stem.

The same letters show like parts.

My invention relates to jury or spare rudders for ships and vessels of all descriptions. 30 By a jury-rudder I mean that one which can be supplied and rigged to vessels to take the place of the permanent steering apparatus when it has been disabled or carried away by an accident or disaster at sea.

My jury-rudder I design to attach to the stern of the vessel directly in a line abaft of the permanent or regular ship's rudder.

The stem of the rudder is seen at *a*. This may be a main boom or spar, or it may be a 40 stick specially carried on board for the purpose; but I desire to specify that any spar or stick having a uniform diameter throughout its length—such as vessels usually carry as extra spars—can be utilized for this purpose.

This spar, which I will now call the "rudder-stem," is seen at *a*. To this, at the lower portion thereof, is attached the blade *b*. The blade may be of one or more parts or pieces, and may be provided beforehand and carried 45 on board the vessel at the commencement of the voyage. It can be made of wood or metal.

It is better of wood, so as to float the iron and relieve the weight on the socket *h*. The blade *b* is connected with the stem by clamps *c*. These clamps are constructed as illustrated in 55 Fig. 3. They consist of two bands of metal, having the lips *d*, semicircular parts *e*, and straight parts *f*. The lips and straight parts are united by the nut-boots *g*, passing through the parts of the clamp, as seen in the drawings. 60 The semicircular parts encompass the stem *a*. The lips *d* unite on a point on the periphery of the stem opposite to where the blade *b* is located. Bringing these lips *d* together binds the semicircular parts closely to the stem *a*. The 65 straight parts *f* lie along on the two faces of the blade *b*, and the bolts *g* pass through the blade, as shown in the drawings, and thus hold the blade in its true relation and contact with the stem and clamp it firmly thereon. The 70 lower end of the stem *a* is stepped into a socket, *h*. This socket is made concave on the upper surface to receive the lower end of the stem, and has a hole through it, through which projects the neck *i* of the thimble. The lower end of 75 the stem *a* fits into an iron thimble, *j*, which thimble forms what I call the "lower" end of the stem. The thimble is properly secured by bolts *k*. It is of thick iron at the bottom, and is secured in its seat in the socket *h* by the 80 screw-bolt *l*, which threads up into a screw-socket in the lower end of the neck *i*.

The socket *h* is the support of the stem *a* at the lower end. This socket *h* is suspended, supported, and held by guys *m* and *n*. The 85 guys *m* extend upwardly and forwardly and run through hawse-ports in the vessel's bulwarks and are secured aboard. The guy *n* extends abaft of the stern of the ship and is secured into the eye *o* on the boom *h*, provided for the purpose. The socket *h* is furnished with proper eyes to receive the guys. The guys are of wire rope, so as to be practically non-elastic, or chains. We have then got the rudder securely stepped at the lower end and 90 provided with a socket, *h*, in which the lower end of the stem can turn as the rudder is moved for steering. The screw-bolt *l* keeps the lower end of the stem down in its socket *h*. The stem is further held by the clamp *p*. This clamp is 95 composed of two strong metal bars bolted together, as seen in the drawings. The portions 100

p' pass on each side of the hull at the stern and the bolts *q* pass through the dead wood or stern-post of the vessel and through the portions *p'*, and so fasten the clamp firmly to the vessel.

5 The two semicircular portions of the clamp encompass the stem, but so as to allow it to turn therein in steering. The lips *r* serve to fasten the two parts of the clamp together at the stern side of the stem. The stem is provided 10 with a metal band, *s*, inside of the circular part of the clamp, in order to avoid chafing. This is seen at *t*. The clamp *p* is supported by three rods, *u v v*.

v v are diagonal rods (with tightening-nuts 15 *w*) bolted to the ship's side and connected with the clamp *p* at *x*. The other rod is seen at *u*, fastened to the ship's stern at the center and attached to the clamp at *y* by a bolt passing through the bifurcation of the rod at its lower 20 end as well as through the two parts of the clamp *p* itself. Near the top of the stem it is further fitted with a bearing, *z*. This is composed of a metal plate, *a'*, bolted to the ship's stern at the proper point and having a semi- 25 circular socket, *b'*; also, of the cap-piece *c'*, so that the two will, when placed together, form the circular hole seen in Fig. 4, and the two parts be united by bolts *d'* passing through the lips *e'*. At this point, also, the stem is protected 30 by a chafing-ring of metal, *f'*, to protect the wood of the stem. *g''* is the tiller, projecting directly astern and properly fastened and clamped to the stem of the rudder.

The tiller can be applied so as to project 35 forward of the stem of the rudder, where the nature and structure of the vessels admit. In case of sea-going steamers it would be necessary to have it as before described. The tiller is provided with blocks and ropes reaching aboard

the vessel, and is worked thereby. These ropes 40 can be operated by winches, or, in the case of sailing vessels, by the barrel of the steering apparatus aboard. Lines *h'* are also attached to the blade of the rudder, as illustrated. They run through sheaves at *i'* and are worked 45 at the same time with the tiller-lines in order to facilitate the turning of the rudder.

I have thus produced a jury-rudder that can be quickly shipped, in case of an accident, to the permanent steering apparatus and firmly 50 secured in place.

It will be seen that the guys *m* and *n* serve to steady the rudder and take the strain during forward or backward motion of the vessel.

What I claim as my invention, and desire to 55 secure by Letters Patent of the United States, is—

1. The combination of the stem *a*, blade *b*, blade-clamps *c*, having the lips *d*, semicircular parts *e* and straight parts *f*, the thimble at the 60 lower end of the stem, with its neck *i* and bolt *l* and chafing-ring *f'* and band *s*, as herein set forth.

2. The combination of the stem *a*, having the thimble, as set forth, blade *b*, clamped, as 65 described, with the clamp *p*, to hold the stem to the vessel's hull, as described, the supports *w u v*, bearings *g*, metal plate *a'*, cap-piece *c'*, the socket *b'*, to support the lower end of the stem, and guys *m* and *n*, as herein specified. 70

In testimony that I claim the foregoing as my own I affix my signature in presence of two witnesses.

JOSEPH WALL.
